(57)

CLAIM

The ornamental design for a fixed blade knife, as shown and described.

DESCRIPTION

FIG. 1 is a perspective view of the fixed blade knife;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines depict portions of the fixed blade knife in which the design is embodied that are not considered part of the claimed design.

1 Claim, 4 Drawing Sheets(56)
